PLASTIC DOILY

William E. Cole, London, England

Application July 5, 1956, Serial No. 42,152

Term of patent 14 years

(Cl. D59—2)

The single figure is a plan view of a plastic doily showing my new design.

The doily is shown over a dark background to bring out the details of the design.

I claim:

The ornamental design for plastic doily, as shown and described.
